UNITED STATES PATENT OFFICE

GUNNER OLSON AND EUGENE H. KEHL, OF CHICAGO, ILLINOIS

HEATER

Application filed June 20, 1927. Serial No. 200,209.

Our invention relates to water heating, and more specifically to the type of water heater adapted for installation as an auxiliary attachment in a boiler, such as the boiler of a 5 hot water or steam heating plant or a boiler for generating steam for power.

Among the objects and advantages of the invention may be enumerated the improvement of this type of heater particularly with 10 respect to convenience of installation, freedom from leakage, operating control, and cleaning and repair.

In the accompanying drawings,

Figure 1 is a sectional view of a complete 15 heater according to the invention;

Figure 2 is an outside end elevation of the same heater;

Figure 3 is a section on line 3-3 of Figure 1;

20 Figure 4 is a perspective view of the valve member;

Figure 5 is a section on line 5-5 of Figure 1;

25 Figure 6 is a section on line 6-6 of Figure 1; and

Figure 7 is a plan view of the valve member looking down from above.

In the embodiment of the invention selected for illustration, the cylindrical tube 10 receives a plug 12 at its extreme inner end. This plug is brazed or welded in place as at 14. The tube is subdivided into two passageways by a central axial partition 16 in the form of a flat plate. The sides of the tube 30 are formed with grooves 17 to receive the edges of the plate, which fits loosely enough to be capable of withdrawal for cleaning. The protuberances on the outside, caused by bending the grooves 17 constitute deflectors

35 to set up advantageous currents in the water outside and improve the heat transfer. The plug 12 carries a flat fin 18 lying in a plane vertical to that of the partition 16. The end of the partition abuts the fin to position the

50 to set up advantageous currents in the water outside and improve the heat transfer. The plug 12 carries a flat fin 18 lying in a plane vertical to that of the partition 16. The end of the partition abuts the fin to position the

the heating will not draw the temper of the plate and weaken it. The brazed end of the tube and the outer end of the plate 16 terminate in the same vertical plane adjacent the face of the cylindrical valve member 24.

55 The valve member proper is provided with a bottom inlet at 26 and a top outlet at 28 separated by a central partition 30, which, when the valve is in the wide open position of Fig. 1, lies in a horizontal plane and abuts the 60 end of the partition 16.

The valve member carries a stem 32, which passes outwardly through the cover plate 34 and a suitable packing 36. The handle 38 by means of which the valve may be rotated is 65

provided with a pointer 40 for the convenience of the operator. A lug 42 on the outer face of the valve member proper moves between fixed lugs 44 and 46 projecting inwardly from the adjacent face of the cover 70

34 to limit the rotation of the valve member to substantially 90 degrees. Referring now more particularly to Figs. 4, 6 and 7, it will be observed that the outlet opening 28 subtends a trifle less than 90 degrees of the circumference of the valve, and that the portion of it which remains open last, as the valve 75

moves to closed position, is V-shaped as at 48, rather than round. This results in a better control of the flow through the device because 80 at small openings the angle of the sides at 48 is steeper than the circular arc indicated at 50 in Fig. 7, and provides a smaller change in the effective area of the opening for a given change in position.

85 It will also be observed that the inlet opening 26 subtends materially more than 90 degrees and that its closing portion is also V-shaped as at 52. Because the toe of this V extends farther than 90 degrees from the opposite side of the opening, a movement of the valve through 90 degrees in a clockwise direction from the position of Fig. 2 will completely close the outlet opening 28 and still leave a small aperture at the inlet. This eliminates 90

95 any complete isolation of the contents of the tube from the rest of the system.

The head 22 is provided with suitable tubular bosses at 54 and 56 communicating with the inlet and outlet, respectively. The lower 100

At its outer end the tube is brazed as at 20 to the main supporting head 22. This is done before the plate 16 is slipped in place, so that

or inlet boss is turned outward at an angle, as clearly shown in Fig. 1. The head is sealed to the face 58 of the boiler by a gasket 60 and to the cover plate 34 by another gasket 62. 5 The gasket 62 is compressed by tightening four bolts 64.

To install the device, the face of the boiler 58 is cut away, as with an acetylene torch, to provide a circular opening at 66 and two diametrically opposite extensions 68 for receiving the fastening bolts 70. The opening 66 receives the lip 72 of the head 22. Each bolt 70 has an integral head 74 abutting the rear surface of the plate 58. Each bolt comprises a 10 straight portion passing through the plate 58 and an inclined portion 76 terminating in a threaded end to receive the fastening nut 78. The head is provided with diametrically opposite bosses, each apertured as at 80 to receive the inclined portion of the bolt and ending at 82 in a plane perpendicular to the axis of the inclined portion to afford a suitable abutment for the packing 79 and nut 78.

Referring now to Fig. 4, in which the position of the edge of the partition is diagrammatically indicated in dotted lines at 16, it will be apparent that further rotation of the valve member in a counter-clockwise direction will not only reduce the area of the inlet 25 and outlet openings controlling the flow through the device, but that the edge of the partition 30 will move out of contact with the partition 16 near the outer periphery of the valve member and leave a direct opening so that water entering at 26 can pass between the front edge of the partition 16 and the edge of the partition 30 directly up to the outlet 28 without passing through the heating tube.

40 When the valve is closed, extensions 84 projecting from the edge of the partition 30 overlie the edge of the partition 16 to provide a joint that is an effective barrier against circulation, as distinguished from leakage. 45 These extensions are on opposite sides of the axis of rotation and also lie on opposite sides of the partition to permit rotation of the valve member to the closed position.

Without further elaboration, the foregoing 50 will so fully explain the gist of our invention that others may, by applying current knowledge, readily adapt the same for use under various conditions of service. It will be obvious that all the features described need not necessarily be employed in conjunction, as they may advantageously be utilized in various combinations and sub-combinations.

What we claim is:—

60 1. A water heater comprising, in combination, a head casing having a tubular portion; an annular flange spaced from the end of said tubular portion; said flange having holes opening through it at its inner surface closely adjacent to said tubular portion; said 65 holes being inclined out and away from the

axis of said tube at an oblique angle; said flange having enlargements around said holes.

2. A head casing for water heaters comprising, in combination, a tubular portion; an annular flange spaced from the inner end of said tubular portion to abut the outer face of a boiler plate; said flange having holes opening through it at its inner surface closely adjacent to said tubular portion; said holes being inclined out and away from the axis of said tube at an oblique angle; said flange having enlargements around said holes; the outer surface of each enlargement being finished perpendicular to the inclined portion of the hole through it. 70 75 80

3. A water heater comprising, in combination, a head casing; a tube brased into said casing; said casing having a tubular portion fitting the end of said tube; an annular flange spaced from the inner end of said tubular portion to abut the outer face of a boiler plate; said flange having holes opening through it at its inner surface closely adjacent to said tubular portion; said holes being inclined out and away from the axis of said tube at an oblique angle; said flange having enlargements around said holes; the outer surface of each enlargement being finished perpendicular to the inclined portion of the hole through it; and fastening bolts in said holes; each bolt being bent to provide an axial portion terminating in an enlarged head and an inclined portion threaded to receive a fastening nut. 85 90 95 100

4. A water heater comprising, in combination, a head casing having inlet and outlet passageways, and an axial bore communicating therewith and open at both ends; a cup shaped cylindrical valve member rotatably mounted in said bore; said valve member having opposite inlet and outlet openings and an intervening partition; a heating tube registering with the open end of said valve; a partition in said tube abutting said valve 105 partition when the valve is in open position; and a cover overlying the closed end of said valve member and fastened to said head casing. 110 115

5. A water heater comprising, in combination, a head casing having inlet and outlet passageways, and an axial bore communicating therewith and open at both ends; a cup shaped cylindrical valve member rotatably mounted in said bore; and a heating tube 120 registering with the open end of said valve.

6. A water heater comprising, in combination, a head casing having inlet and outlet passageways, and an axial bore communicating therewith and open at both ends; a cup shaped cylindrical valve member rotatably mounted in said bore; said valve member having opposite inlet and outlet openings and an intervening partition; a heating tube registering with the open end of said valve; 125 130 135

and a partition in said tube abutting said valve partition when the valve is in open position.

7. A water heater comprising, in combination, a head casing having inlet and outlet passageways, and an axial bore communicating therewith and open at both ends; a cup shaped cylindrical valve member rotatably mounted in said bore; said valve member having opposite inlet and outlet openings and an intervening partition; a heating tube registering with the open end of said valve; a removable partition in said tube abutting said valve partition when the valve is in open position; a cover overlying the closed end of said valve member and fastened to said head casing; registering irregularities of contour on said cover and valve member to limit the relative movement to substantially 90 degrees; and an axial operating shank on said valve member extending out through the cover.

8. A water heater comprising, in combination, a generally cylindrical tube having two inwardly concave grooves parallel to and diametrically opposite each other with respect to the axis; a support brazed to one end of said tube; a plug brazed in the other end of said tube; and a flat partition plate with its edges in said grooves; said plate being free from the effects of the heat of brazing.

9. A water heater comprising, in combination, a generally cylindrical tube having two inwardly concave grooves parallel to and diametrically opposite each other with respect to the axis; a plug in one end of said tube; a partition plate with its edges in said grooves; and an abutment projecting from said plug to limit the movement of said partition.

10. A water heater comprising, in combination, a generally cylindrical tube having two inwardly concave grooves parallel to and diametrically opposite each other with respect to the axis; a supporting head brazed to one end of said tube; a plug brazed in the other end of said tube; a flat partition plate removably inserted with its edges sliding in said grooves; and an abutment projecting from said plug to limit the inward movement of said partition.

11. A water heater comprising a cylindrical heating tube; means for dividing said tube into two passages connected at one end of the tube; and a cylindrical valve coaxial with the tube and controlling the flow into and out of said tube.

12. A water heater comprising a cylindrical valve having opposite inlet and outlet openings; and heating means connected between said openings; said openings being shaped to have near closed position a smaller ratio of change of area to displacement than in positions slightly wider open.

13. A water heater comprising a cylindrical valve having opposite inlet and outlet openings; heating means connected between said openings; one of said openings closing before the other; and means for limiting the closing movement to a position with said outlet completely closed and said inlet still slightly open.

14. A water heater comprising return flow tubing; and a valve controlling the flow through said tubing; said valve having an inlet and an outlet and at wide open position constraining all flow to pass through said tubing; said tubing and valve at intermediate positions permitting some flow to proceed from said inlet to said outlet without passing through said tubing.

15. A water heater comprising, in combination, a head casing; a tube brazed into said casing; said casing having a tubular portion fitting the end of said tube; an annular flange spaced from the inner end of said tubular portion to abut the outer face of a boiler plate; said flange having holes opening through it at its inner surface closely adjacent to said tubular portion; said holes being inclined out and away from the axis of said tube at an oblique angle; said flange having enlargements around said holes; the outer surface of each enlargement being finished perpendicular to the inclined portion of the hole through it; fastening bolts in said holes; each bolt being bent to provide an axial portion and an inclined portion; means at the end of the axial portion to overlie the inner surface of a supporting plate; and fastening means on the end of the inclined portion.

16. A water heater comprising, in combination, a one-piece generally cylindrical tube having opposite portions bent out to form longitudinal grooves; and a partition with its edges in said grooves.

17. A water heater comprising, in combination, a one-piece generally cylindrical tube having opposite portions bent out to form longitudinal grooves; and a partition plate removably inserted with its edges sliding in said grooves.

18. A water heater comprising, in combination, a horizontal tube; and deflectors running longitudinally along the sides of said tube to deflect a current of liquid descending over the upper half of said tube and shield a rising current of liquid bathing the lower half of said tube.

19. A water heater comprising, in combination, a flanged head; and bolts for bolting said head against the face of a boiler; said bolts having irregularities of shape to abut cylindrical portions of the head and keep the bolts from turning when drawing up.

20. A water heater comprising, in combination, a cup shaped valve having an open

end and inlet and outlet openings in its side wall; a heating tube coaxial with said valve and communicating with said open end; and partition means operative when said valve is fully open to direct flow from said inlet opening to the remote end of said tube and back to said outlet; said partition means including a stationary portion mounted in said tube and a movable portion mounted in said valve to move therewith, said movable portion lying in the plane of said stationary portion when the valve is wide open, whereby in partially closed positions there is substantial leakage through said partition means.

21. A water heater comprising, in combination, a cup shaped valve having an open end and inlet and outlet openings spaced therefrom; and heating tube means communicating with said open end.

22. A water heater comprising, in combination, a cup shaped valve having an open end and inlet and outlet openings spaced therefrom; a heating tube communicating with said open end; and partition means operative when said valve is open to direct flow from the said inlet opening to the remote end of said tube and back to said outlet; said partition means including a stationary portion mounted in said tube and a movable portion mounted in said valve to move therewith, said movable portion lying in the plane of said stationary portion when the valve is wide open, whereby in partially closed positions there is substantial leakage through said partition means.

23. A water heater comprising, in combination, a cup shaped valve having an open end and inlet and outlet openings spaced therefrom; heating tube means communicating with said open end; and partition means operative when said valve is open to direct flow from said inlet opening to the remote end of said tube and back to said outlet; said partition means including a movable portion mounted in said valve.

24. A water heater comprising, in combination, a cup shaped valve having an open end and inlet and outlet openings spaced therefrom; and a heating tube coaxial with said valve and communicating with said open end.

25. A water heater comprising, in combination, a cup shaped valve having an open end and inlet and outlet openings spaced therefrom; a heating tube communicating with said open end; and partition means operative when said valve is open to direct flow from said inlet opening to the remote end of said tube and back to said outlet; said partition means in partially closed positions permitting substantial leakage.

26. Water heating equipment comprising a boiler having a pressure retaining wall; said wall having an aperture, a heater entered

in said aperture; said aperture being of generally smooth contour except for small notches cut away at predetermined points; and fastening bolts for said heater; said bolts passing through said notches.

27. Water heating equipment comprising a boiler having a pressure retaining wall; said wall having an aperture, a heater entered in said aperture; said aperture being of generally smooth contour except for small notches cut away at predetermined points; fastening bolts for said heater; said bolts passing through said notches; and a gasket between said wall and heater circumscribing the heater and the bolts.

28. A water heater comprising, in combination, a flanged head; and bolts for bolting said head against the face of a boiler; said bolts having outwardly bent portions on the outside of the boiler; and means other than said outwardly bent portions for keeping said bolts from turning when drawing up.

29. A water heater comprising, in combination, a flanged head; and bolts for bolting said head against the face of a boiler; said bolts having outwardly bent portions on the outside of the boiler, and means inside the boiler for keeping said bolts from turning when drawing up.

30. In a device of the class described; a boiler having an apertured plate; a casting positioned at the aperture, said casting having a flange overlying the edges of the aperture; a peripheral gasket forming a seal between said flange and plate; bolts passing through flange and plate inside said gasket; and sealing gaskets at the outer ends of said bolts.

In testimony whereof, we have signed our names to this specification.
